UNITED STATES PATENT OFFICE

ALEXANDER GEIGES, OF EAST ORANGE, NEW JERSEY, ASSIGNOR TO H. L. JUDD COMPANY, INC., OF WALLINGFORD, CONNECTICUT, A CORPORATION OF DELAWARE

DESIGN FOR A DRAPEY-ROD END PIECE

Application filed August 27, 1929. Serial No. 32,553. Term of patent 3½ years.

To all whom it may concern:

Be it known that I, ALEXANDER GEIGES, a citizen of the United States, residing at East Orange, in the county of Essex and State of New Jersey, have invented a new, original, and ornamental Design for a Drapery-Rod End Piece, of which the following is a specification, reference being had to the accompanying drawing, forming part thereof.

Fig. 1 is a front elevation of a drapery rod end piece, showing my new design, and Fig. 2 is an edge view of the same.

I claim:

The ornamental design for a drapery rod end piece, as shown.

ALEXANDER GEIGES.
